(57) **CLAIM**

The ornamental design for a wand, as shown and described.

DESCRIPTION

FIG. 1 is a perspective view of a wand in accordance with our design;

FIG. 2 is a front elevation view of the wand in accordance with our design, the opposite view being a mirror image of that shown;

FIG. 3 is a side elevation view of the wand in accordance with our design, the opposite view being a mirror image of that shown;

FIG. 4 is a top plan view of the wand in accordance with our design; and,

FIG. 5 is a bottom plan view of the wand in accordance with our design.

The broken lines showing environmental structure are for illustrative purposes only and form no part of the claimed design.
